(57) **CLAIM**

I claim the ornamental design for a beverage insulator, as shown and described.

DESCRIPTION

FIG. 1 is a perspective view of a beverage insulator, showing my new design in an open position;

FIG. 2 is a perspective view thereof, illustrated in a closed position;

FIG. 3 is a front elevational view of FIG. 2;

FIG. 4 is a rear elevational view of FIG. 2;

FIG. 5 is a right-side elevational view of FIG. 2, the left-side elevational view being a mirror image thereof;

FIG. 6 is a top plan view of FIG. 2;

FIG. 7 is a bottom plan view of FIG. 2; and,

FIG. 8 is a left-side elevational view of FIG. 1, the right-side elevational view being a mirror image thereof.

The broken lines showing a soda can in FIG. 1 and an aperture in FIG. 7 depict environmental matter and form no part of the claimed design.
